Primary Examiner — Paula Allen Greene*(74) Attorney, Agent, or Firm* — Altera Law Group, LLC(57) **CLAIM**

The ornamental design for an earphone, as shown and described.

DESCRIPTION

FIG. 1 is a perspective view of the earphone.

FIG. 2 is a front view thereof.

FIG. 3 is a back view thereof.

FIG. 4 is a side view thereof.

FIG. 5 is the other side view thereof.

FIG. 6 is a top view thereof.

FIG. 7 is a bottom view thereof.

FIG. 8 is another perspective view of the earphone.

FIG. 9 is a front view thereof.

FIG. 10 is a back view thereof.

FIG. 11 is a side view thereof.

FIG. 12 is the other side view thereof.

FIG. 13 is a top view thereof; and,

FIG. 14 is a bottom view thereof.

The features shown in broken lines depict environmental subject matter only and form no part of the claimed design.

1 Claim, 8 Drawing Sheets(56)
